UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed June 5, 1924. Serial No. 717,920.

This invention relates to typewriting of the class known as continuous billing, in which class of work a multiple ply continuous work-web ordinarily is interleaved with 5 carbons carried by a carbon-carrier that is advanceable toward the platen at line-feeding and retractile to effect relative shifting of the work-web and carbons upon displacement of the platen.

10 The present invention has certain features in common with my pending application, Serial No. 717,009, filed May 31, 1924. That is, it is an object of the present invention, as in the application referred to, to obviate 15 the displacing of the platen and to eliminate the carbon-carrier altogether.

It is a further object of the present invention to provide rapid operating means for 20 locating the work-web and carbons in exact carbon-shifting position for clamping the carbons stationary and for then effecting a mechanically measured shifting of the work-web relatively to the carbons, whereby 25 the shifting may be effected quickly and accurately, and without reliance upon the operator's observation of the work-web and the carbons.

In attaining the above-mentioned objects, 30 use is made of discrete carbons of substantially greater width than the work-web, which carbons are preferably interleaved with the work-web in such manner that they protrude at both side margins beyond the sides of the work-web. The carbons are 35 unattached to the machine, and are feedable by and with the work-web upon rotation of the platen. When, at the conclusion of typing a form, it is desired to effect a relative shift between the work-web and carbons, the 40 platen is rotated backward to feed the carbons to a definite carbon-shifting position in which they are straight and free of the platen at the rear thereof. Provision is made of means to clamp the carbons stationary 45 in this carbon-shifting position, while the work-web is advanced a form-length by rotation of the platen.

Platen-sweep mechanism is provided for 50 rapidly imparting a mechanically measured, backward rotation to the platen to retract the carbons and the interleaved work-web from final writing position to carbon-shifting position, and for rapidly imparting a mechanically measured forward rotation to 55 the platen to advance the work-web exactly

a form length while the carbons are held stationary by the carbon clamping means. The second mentioned operation of the platen-sweep mechanism effects a measured relative shift of the work-web and carbons, 60 and, in addition, mechanically locates the work-web for severing. The platen-sweep mechanism comprises a platen-sweep handle which is normally connected to the platen to travel whenever the platen is rotated, but 65 which is disconnectible from the platen for movement relatively thereto, when desired.

In beginning the work upon the machine, the carbons are first interleaved with the 70 second form-section upon the work-web, and the web and carbons are then introduced into the machine from the rear, the carbons being brought to their carbon-shifting position, and the platen-sweep handle being located at the rear limit of its movement. 75 The platen is then advanced, by the platen-sweep handle if desired, to feed the work-web and carbons forward to the first writing line position of the second web-section, and the typing of this section is done in the 80 usual way, the platen-sweep handle continuing to advance as the work is fed forward. At the conclusion of such typing, the platen-sweep handle is pushed to the rear limit of 85 its movement against a rear stop, and this movement of the handle, of course, rotates the connected platen backward to return the carbons to the carbon-shifting position. During this backward movement the work-web and carbons move in unison. The 90 clamps are applied to clamp the protruding margins of the carbons, independently of the work-web, to detain the carbons stationary and the platen-sweep handle is next drawn forward rapidly until arrested in a definite 95 position by an adjustable stop located at a predetermined, measured distance from the fixed rear stop, to produce a relative shift of exactly a form-length.

This position of the work-web may 100 conveniently be used as a web-severing position, and the machine is accordingly provided with a web-severing knife, mounted to register with the leading edge of the form just typed, in the position occupied by it at this stage of the operation. The form-section preceding the one just typed is, therefore, torn off by the aid of the knife at this time.

The operator next disconnects the platen-sweep handle from the platen, moves it to 110

the rear into engagement with its fixed stop, and there reconnects it to the platen. At this stage, the clamps are moved to ineffective positions and the platen is rotated a short distance to advance the carbons and the fresh form-section, with which the carbons have become interleaved by reason of the relative shifting, to first writing line position. This completes the cycle of operations which is repeated for each succeeding form-section.

In accordance with one feature of the invention, provision is made of means, actuated by the platen-sweep handle, for automatically rendering the carbon-clamps effective and ineffective at the appropriate times. To this end, a clamp-controlling member is arranged to be engaged and actuated by the platen-sweep handle in the last portion of its backward movement, and connections are provided from this member to the clamp to cause the clamp to be rendered alternately effective and ineffective by successive actuations of said member. The arrangement is such that the platen-sweep handle, in the last part of its rearward stroke whereby the work-web and carbons are retracted in unison to carbon-shifting position, actuates the clamp-controlling member to snap the clamps to effective positions, and, in the past part of its other rearward stroke, which is an idle stroke, actuates the member to render the clamps ineffective, so that the carbons may be fed forward with the work-web.

It will be seen that the platen-sweep mechanism accomplishes the relative shifting of the carbons and work-webs very rapidly, and that its operation is measured at every stage, so that it is unnecessary for the operator to see the position of the carbons, or to observe the relation of the work-web to them, either at the beginning or at the termination of the carbon-shifting operation. The operator, at the conclusion of writing a form section, is required merely to move the platen-sweep handle backward against the rear stop, then forward against the adjustable front stop, then to tear off the end section of the web, move the handle idly to the rear stop and then forward a short distance to advance the work to writing position.

Other features and advantages will hereinafter appear.

55 In the accompanying drawings,

Figure 1 is a side elevation, partly broken away, showing the novel mechanism of the present invention and so much of the old mechanism as is necessary to an understanding of the invention.

Figure 2 is a diagrammatic side elevation, showing the parts in positions occupied by them in the course of typing a form-section.

60 Figure 3 is a front elevation of the mechanism shown in Figure 1.

Figure 4 is a fragmentary horizontal sectional view, showing the mechanism at the right end of the machine.

Figure 5 is a diagrammatic side elevation, showing the mechanism and particularly the members of the adjustable stops in the positions occupied by them when typing is effected at the lower end of a form.

Figure 6 is a diagrammatic side elevation, showing the parts in the positions occupied when the platen-sweep handle has been moved to the rear to locate the carbons in carbon-shifting position.

Figure 7 is a diagrammatic side elevation, showing the parts in web-severing position, that is, just at the conclusion of a carbon-shifting operation.

Figure 8 is a diagrammatic side elevation, showing the parts in the positions occupied after the end web-section has been severed and the platen-sweep handle has been returned to the rear, but before said handle has been reconnected to the platen.

The typewriting machine comprises a cylindrical platen 10 journaled by its axle 11 in ends 12 of a platen-frame 13 that is movable in letter feed and return directions in the usual manner. Feed-rolls 14 co-operate with the platen to feed back and forth a continuous work-web 15 that is led to the platen over a high rear paper-table 16 from a source of supply.

In beginning the work upon the work-web 15, discrete carbons 17 of greater width than the work-web are interleaved with the second form-section thereof in such manner that they protrude at both side margins beyond the sides of the work-web; or, if a fan-fold web is used, so that each carbon protrudes at one of its side margins. The work-web 15 with the interleaved carbons 17 is introduced into the machine from the rear of the platen and is advanced until the carbons are located in the position shown in Figure 1, which is the carbon-shifting position.

At its right end the platen-axle 11 has a small gear 18 fast upon it which meshes with a larger gear 19 fast upon a shaft 20 journaled in a sleeve 21 that forms part of a supporting bracket 22 carried by a base-plate 23 secured upon the right end 12 of the platen-frame 13. The shaft 20 also has fast upon it a driver wheel 24 having sharp pointed teeth 25 for interlocking engagement with sharp pointed teeth 26 of a latch 27 carried by a platen-sweep handle 28 which is rotatably mounted upon the shaft 20. A spring 29 connected to the platen-sweep handle 28 and to the latch 27 normally maintains the latch in engagement with the driver wheel 24 and hence maintains driving connection between the platen-sweep handle and the platen.

65 The latch 27 has elongated slots 30

through which pass the shanks of screws 31 that are threaded into the platen-sweep handle 28 to hold the latch upon the handle but in a manner to permit movement of the latch 5 toward and from the driver wheel 24. When the work-web 15 and carbons 17 have been brought to the carbon-shifting position described, the latch 27 may be moved longitudinally of the platen-sweep handle 28 by 10 means of a finger-piece 32 to disconnect the handle from the platen, so that the handle may be moved to the rear until arrested by engagement of a projection 33 upon it with the base-plate 23. The handle 28 in this 15 position is connected to the platen by permitting the spring 29 to draw the latch 27 toward the driver wheel 24, so that the handle may be actuated to feed the work forward to typing position, and may be advanced by 20 the platen at the line-spacing of the work as the typing proceeds. When the form-section with which the carbons 17 are interleaved has been advanced to typing position and has been typed, the platen-sweep handle 25 is thrust to the rear to its initial position as shown in Figures 1 and 6, and this retracts the work-web 15 and the interleaved carbons 17 to the position shown in Figures 1 and 6, that is, to their initial position with the 30 carbons in carbon-shifting position. At this stage, clamps 34 are made effective to grip the protruding side margins of the carbons 17 at their ends remote from the platen to hold the carbons stationary while the work-web 15 is advanced relatively to them. The means for clamping the carbons will be described in detail later.

The platen-sweep handle 28 is next drawn forward a distance sufficient to advance the work-web 15 exactly a form length, (see 40 Figure 7), whereby the carbons 17 are stripped from the typed web-section and interleaved with the next section of the web. For the purpose of measuring this relative shifting, provision is made of an adjustable stop 35 arranged to intercept a projection 36 on the platen-sweep handle and to arrest the handle. The stop 35 is carried by an arm 37 rotatably mounted on the shaft 20, that carries a screw 38 which is arranged to be turned to fit between teeth 39 of a segment 45 forming part of the bracket 22. These teeth 39 are located at spaces corresponding to line-space intervals, so that the advance of the work-web 15 relative to the carbons 17 55 may be varied in accordance with the length of form used.

The position of the work-web 15 at the 60 conclusion of this relative shifting operation is always the same, that is, the line of division between the end section of the work-web and the section which has just been typed and stripped from the carbons occupies a definite uniform position. This position, 65 therefore, may conveniently be the web-

severing position. Provision is made of a knife 41 which is mounted on standards 42 extending upward from the bracket 22 and from the left-hand base-plate 23. These standards are provided with threaded openings 43 at equally spaced intervals, any pair of which may be utilized for the reception of knife supporting thumb screws 44, so that the knife 41 may be adjusted in various positions according to the length of the form-section used. 70

An upwardly extending web-supporting finger 45 is mounted upon a cross-bar 46 connecting the standards 42, to hold the web 15 conveniently near the knife 41, so that the operator may seize it readily, and to prevent the web's passing a second time around the platen. 80

After the severing of the work-web, the platen-sweep handle 28 is disconnected from the platen by pulling outward on the finger-piece 32 and the handle is moved to its extreme rear position and there reconnected to the platen by releasing the finger-piece. 85 At the conclusion of this backward movement of the platen-sweep handle 28 the clamps 34 are made ineffective, to permit the carbons 17 to be advanced with the work-web 15 to writing position. 90

Mechanism is provided for automatically 95 rendering the clamps effective and ineffective at the appropriate times. The clamps 34 are fast upon a transversely extending shaft 47 which also has fast upon it an operating arm 48. A spring 49 connected to the operating arm and to a projection 50 on the rear paper-table tends always to move the clamps 34 to effective position. A cam-follower 51 mounted in guides 52 and connected to the arm 48 rides upon the surface of a cam 53 fast to a shaft 54 journaled in brackets 55. This cam 53 has alternate high and low parts which are so arranged that the clamps 34 are rendered ineffective when a high part of the cam engages the follower 51 and are permitted to be made effective by the spring 49 when a low part of the cam engages the follower. The cam 53 is rotated step by step to bring its high and low parts alternately to effective position by means of a 100 ratchet-wheel 56 fast on the shaft 54. 105

An oscillatory arm 57 loose on the shaft 54 carries a pawl 58 for co-operation with the ratchet-wheel 56. The oscillatory arm 57 also carries a pitman 59 which is held by a guide 60 in the path of the platen-sweep handle 28. When the platen-sweep handle 28 is moved to its extreme rear position it engages the pitman 59 on the oscillatory arm 57 to feed the ratchet-wheel 56 one tooth space. This serves to bring a high part of the cam 53 opposite the follower 51 if a low part was previously effective, or to bring a low part opposite the follower if 110 a high part was previously effective. 115

A spring detent 61 co-operates with the ratchet-wheel 56 to control the exact length of the feeding steps. When the platen-sweep handle 28 is moved away from its rearward position, the oscillatory arm 57 is retracted to its normal position by a spring 62 connected to said arm and to one of the guides 52 on the rear paper-table.

It will now be understood that when the platen-sweep handle 28 is first moved to the rear to retract the carbons 17 and the work-web 15 together to the position of Figure 6, the movement of the pitman by the handle causes the clamps to be made effective. The cam 53 is so contoured that the spring 49 is caused to snap the clamps 34 to effective position at the very end of the rearward movement of the platen-sweep handle 28. The handle 28 is next drawn forward to advance the work-web while the carbons are held stationary by the clamps 34, and is then disconnected from the platen and returned idly to the rear. At the conclusion of the idle rearward movement of the platen-sweep handle 28, the actuation of the pitman 59 by said handle causes the clamps 34 to be made ineffective (see Figure 8), so that the carbons 17 may be advanced with the work-web 15 to writing position.

It will be noted that the carbons 17 are drawn entirely clear of the platen, at the rear thereof, for carbon-shifting, and hence that the leading edge of the work-web section with which they are interleaved is drawn a substantial distance below the line of writing. The stop 35 is effective to arrest rotation of the platen when the work-web has been advanced exactly a form length from this position at carbon-shifting. It is desirable, however, to permit a greater advance of the handle 28 at typing in order to permit typing to be effected near the bottom of the form, that is, in order that the leading edge of the form may be fed from carbon-shifting position around to the line of writing and then advanced substantially a form length from that point. The stop 35 is therefore constructed to arrest the platen-sweep handle 28 when the handle is advanced rapidly as at carbon-shifting, but to permit the handle to pass it when the handle is advanced slowly as at line-spacing.

To this end the stop 35 is pivoted upon the arm 37 and normally urged in a counter-clockwise direction by a spring 60^a, as viewed in Figures 1, 5 and 7, to maintain its nose 61^a clear of the projection 36 carried by the platen-sweep handle 28. The stop 35 has a tail 62^a which extends into the path of a second projection 63 carried by the platen-sweep handle 28. The arrangement is such that the second projection 63 strikes the tail 62^a at the advance of the handle swinging the stop 35 clockwise to throw the nose 61^a into the path

of the projection 36 (see Figure 7). If the handle 28 is being advanced rapidly, the projection 36 engages the nose 61^a and stops the handle before the nose 61^a has had time to return to its normal position. If the handle 28 is being advanced slowly, however, the nose 61^a returns to its normal position beyond the path of the projection 36 before the projection 36 can engage it and offers no obstruction to the advance of the handle, so that the line-feeding of the work can be continued to the bottom of the form.

The knife-supporting standards 42 are supported at their lower ends upon the forward ends of the base-plates 23, and are additionally supported by brackets 64 extending upward from the rear ends of said base-plates. The standards 42 are further combined with the rear paper-table 16, to form a rigid truss therewith, by means of webbing 65. In this way, the standards 42 and the paper-table 16 are caused to brace one another.

It has been pointed out that the stop 35 may be adjusted by line-space units as determined by the usual line-space ratchet-wheel 66 and co-operating detent 67. Since the platen will always be advanced, therefore, a whole number of line-spaces, the detent 67 will help to detain the platen stationary during the idle backward movement of the handle, and the handle can be connected to the platen when at the rear limit of its movement without altering the position of the platen at all.

The form can be varied in length within a wide range so long as it is of a length equal to a whole number of line-spaces. Since a distance of two form-lengths intervenes between the rear ends of the carbons in carbon-shifting position and the knife, the provision of openings 43 at double-line-space intervals for the attachment of the knife will accommodate single-line-space variations in the length of form used.

Variations may be resorted to within the scope of the invention, and portions of the improvements may be used without others.

Having thus described my invention, I claim:

1. In a continuous billing typewriting machine, the combination with a revoluble platen, of a set of discrete carbons feedable around the platen with an interleaved work-web, means for holding the carbons stationary in a definite predetermined carbon-shifting position wherein they are straight and free of the platen, means for sweeping the platen forward and backward, means for limiting the backward sweep of the platen to arrest the work-web and carbons in carbon-shifting position, and means for limiting the forward sweep of the platen to arrest the work-web when it has been advanced a

- predetermined distance from the carbon-shifting position.
2. In a continuous billing typewriting machine, the combination with a revoluble platen, of a set of discrete carbons feedable around the platen with an interleaved work-web, means operable to clamp the carbons stationary in a definite predetermined carbon-shifting position wherein they are straight and free of the platen, means for sweeping the platen forward and backward, means for limiting the backward sweep of the platen to arrest the work-web and carbons in exact carbon-shifting position, means for limiting the forward sweep of the platen to arrest the work-web when it has been advanced exactly a form length from the carbon-shifting position, and a web-severing knife located to register with the line of division between two form-sections on the work-web at the conclusion of said forward sweep of the platen.
3. In a continuous billing typewriting machine, the combination with a revoluble platen, of a set of discrete carbons feedable around the platen with an interleaved work-web, means for holding the carbons stationary in a definite predetermined carbon-shifting position wherein they are straight and free of the platen, means for sweeping the platen backward to locate the work-web and carbons in carbon-shifting position, and for sweeping the platen forward to effect a relative shift of the work-web and carbons, means for limiting the backward sweep of the platen to arrest the work-web and carbons in exact carbon-shifting position, means for limiting the forward sweep of the platen to arrest the work-web when it has been advanced exactly a form length from the carbon-shifting position, and means operable to disconnect the platen-sweep means from the platen to permit retraction of said means independently of the platen, following the carbon-shifting sweep of the platen.
4. In a continuous billing typewriting machine, the combination with a revoluble platen, of a set of discrete carbons feedable around the platen with an interleaved work-web, means for holding the carbons stationary in a definite carbon-shifting position wherein they are straight and free of the platen, means for sweeping the platen backward to locate the work-web and carbons in a definite predetermined carbon-shifting position, and means operated by said platen-sweeping means to clamp the carbons independently of the work-web to hold them stationary in carbon-shifting position while the work-web is advanced relatively to them.
5. In a continuous billing typewriting machine, the combination with a revoluble platen, of a set of discrete carbons feedable around the platen with an interleaved work-web, means for rotating the platen backward to locate the work-web and carbons in a definite predetermined carbon-shifting position, and for rotating the platen forward to advance the work-web for shifting it relatively to the carbons, clamping means operable prior to the relative shift of the work-web and carbons to clamp the carbons stationary, and operable after such relative shift to release the carbons, and mechanism operated by the platen-rotating means to control the effective and ineffective condition of said clamping means.
6. In a continuous billing typewriting machine, the combination with a revoluble platen, of a set of carbons feedable around the platen with an interleaved work-web, means for clamping the carbons stationary in a definite carbon-shifting position wherein they are straight and free of the platen, and a single platen-sweep handle connected to sweep the platen backward to locate the work-web and carbons in carbon-shifting position, and to sweep the platen forward to effect a relative shift of the work-web and carbons.
7. In a continuous billing typewriting machine, the combination with a revoluble platen, of a set of carbons feedable around the platen with an interleaved work-web, means for clamping the carbons stationary in a definite carbon-shifting position wherein they are straight and free of the platen, a single platen-sweep handle connected to sweep the platen backward to locate the work-web and carbons in carbon-shifting position, and to sweep the platen forward to effect a relative shift of the work-web and carbons, and means operated by the platen-sweep handle in said backward platen-sweeping movement to make the carbon-clamping means effective.
8. In a continuous billing typewriting machine, the combination with a revoluble platen, of a set of discrete carbons feedable around the platen with an interleaved work-web, means for imparting a mechanically-measured movement to the work-web and carbons to feed them together from final writing position to a definite predetermined carbon-shifting position, and means for clamping the carbons stationary in said carbon-shifting position while the work-web is shifted relatively to them.
9. In a continuous billing typewriting machine, the combination with a revoluble platen, of a set of carbons feedable around the platen with an interleaved work-web, means for clamping the carbons stationary in a definite carbon-shifting position, a platen-sweep handle movable from a mechanically-limited rear position to a mechanically-limited forward position for imparting a mechanically-measured forward movement to the work-web independently of the carbons while the carbons are held station-

- ary by the carbon-clamping means, the platen-sweep handle being disconnectible from the platen and movable idly from said forward position to said rearward position 5 following the measured feeding of the work-web, and means operated by the idle rearward movement of the platen-sweep handle to release the carbons from said clamping means.
- 10 10. In a continuous billing typewriting machine, the combination with a revoluble platen, of a set of carbons feedable around the platen with an interleaved work-web, means for holding the carbons stationary in 15 a definite predetermined carbon-shifting position while the work-web is advanced relatively to them, a platen-rotating handle for moving the work-web and carbons from final writing position to carbon-shifting position, 20 and a stop for limiting the movement of the platen-rotating handle to the carbon-shifting position, the handle being connected to the platen to be advanced by it at line-spacing of the work, so that the return of 25 the handle to the stop will always return the work-web and carbons to the position originally occupied by them with the handle at the stop.
11. In a continuous billing typewriting 30 machine, the combination with a revoluble platen, of a set of carbons feedable around the platen with an interleaved work-web, means for holding the carbons stationary in 35 a definite predetermined carbon-shifting position while the work-web is advanced relatively to them, and a platen-sweep handle for rotating the platen to feed the work-web and carbons from final writing position to said carbon-shifting position.
- 40 12. In a continuous billing typewriting machine, the combination with a revoluble platen, of a set of discrete carbons, means to conduct the carbons and an interleaved work-web to the platen from the rear thereof and to support the carbons in a definite 45 predetermined carbon-shifting position at the rear of the platen while the work-web is advanced relatively to them, means for detaining the carbons stationary during such 50 relative advance of the work-web, and means for measuring said advance of the work-web.
13. In a continuous billing typewriting 55 machine, the combination with a revoluble platen, of a set of discrete carbons feedable around the platen with an interleaved work-web, means for imparting a mechanically measured movement to the work-web and carbons in one direction to feed them together from final writing position to a definite 60 predetermined carbon-shifting position and for imparting a mechanically measured movement to the work-web in the opposite direction to effect a relative shift between the work-web and carbons, and means for clamp- 65 ing the carbons stationary in carbon-shifting position during the latter movement of the work-web.
14. In a continuous billing typewriting 70 machine, the combination with a revoluble platen, of a set of discrete carbons feedable around the platen with an interleaved work-web, means operable to clamp the carbons stationary in a definite predetermined carbon-shifting position wherein they are 75 straight and free of the platen, means for sweeping the platen forward and backward, means for limiting the backward sweep of the platen to arrest the work-web and carbons in exact carbon-shifting position, means 80 for limiting the forward sweep of the platen to arrest the work-web when it has been advanced exactly a form length from the carbon-shifting position, a web-severing knife located to register with the line of division 85 between two form-sections of the work-web at the conclusion of said forward sweep of the platen, the means for limiting the forward sweep of the platen being adjustable to take care of different lengths of forms, 90 and means for adjusting the knife to correspond to the adjusted positions of said sweep-limiting means.
15. In a continuous billing typewriting 95 machine, the combination with a revoluble platen, of a set of discrete carbons feedable around the platen with an interleaved work-web, means operable to clamp the carbons stationary in a definite predetermined carbon-shifting position wherein they are 100 straight and free of the platen, means for sweeping the platen forward and backward, means for limiting the backward sweep of the platen to arrest the work-web and carbons in exact carbon-shifting position, means 105 for limiting the forward sweep of the platen to arrest the work-web when it has been advanced exactly a form length from the carbon-shifting position, a web-severing knife located to register with the line of division 110 between two form-sections on the work-web at the conclusion of said forward sweep of the platen, the means for limiting the forward sweep of the platen being adjustable to change the extent of forward sweep by 115 any whole number of line-spaces, and means for adjusting the knife at double line-space intervals to correspond with the adjustments of said sweep-limiting means.
16. In a continuous billing typewriting 120 machine, the combination with a revoluble platen, of a set of carbons, means for locating the carbons and an interleaved work-web in a definite predetermined carbon-shifting position at a substantial distance from the writing line of the machine, means for holding the carbons stationary in said position, means normally connected to the platen to sweep the platen while the carbons are 125 held stationary, and a stop for the platen- 130

sweep mechanism, said stop being constructed to arrest the platen-sweep mechanism at the rapid advance of the platen when the work-web has been swept forward 5 a form length, but to permit the work to be advanced more than a form length from carbon-shifting position when the platen is advanced slowly at typing.

17. In a continuous billing typewriting 10 machine, the combination with a revoluble platen, of a set of carbons, means for locating the carbons and an interleaved work-web in a definite predetermined carbon-shifting position, means for detaining the carbons in said position while the work-web 15 is advanced relatively to them, platen-sweep mechanism for advancing the work-web relatively to the carbons, and means for arresting the platen-sweep mechanism when 20 the work-web has been advanced a form length from carbon-shifting position, said means comprising a pivoted stop, a spring normally holding the stop in an ineffective position, and a tail on the stop engageable 25 by the platen-sweep handle to rock the stop to effective position, the arrangement being such that the handle will engage the stop in effective position when advanced rapidly, but that the spring will restore the stop 30 to ineffective position without arresting the handle when the handle is advanced slowly.

18. In a continuous billing typewriting 35 machine, the combination with a revoluble platen, of a set of carbons, means for detaining the carbons stationary in a definite carbon-shifting position while the work-web is advanced relatively to them, platen-sweep mechanism connected to the platen to sweep it for effecting the advance of the work-web 40 relatively to the carbons and also advanceable by the platen at typing in preparation for a measured retraction by the handle of the work-web and carbons together to carbon-shifting position, and 45 means constructed and arranged to arrest the advance of the platen-sweep handle at carbon-shifting when the work-web has been advanced a form length from carbon-shifting position, but to permit a greater 50 advance of the work-web and carbons together at typing.

19. In a continuous billing typewriting 55 machine, the combination with a revoluble platen, of a set of discrete carbons, a platen-sweep handle arranged to be advanced with and by the platen at typing, then to be retracted to return the work-web and carbons to a definite predetermined carbon-shifting position, then to be advanced to feed the work-web a form length relatively 60 to the carbons, and then to be retracted idly while disconnected from the platen for reconnection to the platen at a different point, 65 clamps for holding the carbons stationary in carbon-shifting position, and controlling

mechanism for the clamps comprising a spring urging the clamps to effective positions, a cam follower for moving the clamps to ineffective positions, a cam having alternate high and low parts to make the clamps alternately effective and ineffective, and means operated by the backward movements of the platen-sweep handle to feed the cam, the arrangement being such that the clamps are made effective by the movement of the handle that returns the work-web and carbons to carbon-shifting position and are made ineffective by the idle backward movement of the platen-sweep handle.

20. In a continuous billing typewriting machine, the combination with a revoluble platen, of a set of discrete carbons, a platen-sweep handle arranged to be advanced with and by the platen at typing, then to be retracted to return the work-web and carbons to a definite predetermined carbon-shifting position, then to be advanced to feed the work-web a form length relatively to the carbons, and then to be retracted idly while disconnected from the platen for reconnection to the platen at a different point, clamps for holding the carbons stationary in carbon-shifting position, and means operated by the backward movement of the platen-sweep handle that returns the work-web and carbons to carbon-shifting position to snap the clamps to effective positions.

21. In a continuous billing typewriting machine, the combination with a revoluble platen, of a set of discrete carbons, a platen-sweep handle arranged to be advanced with and by the platen at typing, then to be retracted to return the work-web and carbons to a definite predetermined carbon-shifting position, then to be advanced to feed the work-web a form length relatively to the carbons, and then to be retracted idly while disconnected from the platen for reconnection to the platen at a different point, clamps for holding the carbons stationary in carbon-shifting position, a pawl operable by the backward movements of the platen-sweep handle, a ratchet feedable step by step by the pawl, a cam feedable by the ratchet, and mechanism controlled by the cam to render the clamps alternately effective and ineffective at the backward movements of the platen-sweep handle.

22. In a continuous billing typewriting machine, the combination with a revoluble platen, of a set of discrete carbons, a platen-sweep handle arranged to be advanced with and by the platen at typing, then to be retracted to return the work-web and carbons to a definite predetermined carbon-shifting position, then to be advanced to feed the work-web a form length relatively to the carbons, and then to be retracted idly while disconnected from the platen for reconnection to the platen at a different point, clamps for holding the carbons stationary in carbon-shifting position, and controlling

tion to the platen at a different point, clamps for gripping the side margins of the carbons independently of the work-web for holding the carbons stationary in carbon-shifting position, a rock-shaft on which the clamps are mounted, a spring normally urging the rock-shaft in a direction to make the clamps effective, a cam-follower for holding the clamps ineffective, and a cam 10 controlling the follower and arranged to be operated by the backward movement of the platen-sweep handle that returns the work-web and carbons to carbon-shifting position, the cam having a sudden drop arranged to be brought opposite the follower by said feeding to permit the spring to snap the clamps to effective positions.

23. In a continuous billing typewriting machine, the combination with a revolute 15 platen, of a high paper-table at the rear of the platen to support the work-web and

carbons in a carbon-shifting position, a knife-supporting frame at the front of the platen, a work-severing knife on the frame, and webbing connecting the high rear 25 paper-table and the knife-supporting frame to co-operate with them to form a rigid truss, so that each supports and reinforces the other.

24. In a continuous billing typewriting 30 machine, the combination with a revolute platen, of a knife-supporting frame at the front of the platen, a knife supported upon the frame for severing the work-web, and an upwardly-extending web-supporting finger carried by the frame behind the work-web to hold the web conveniently near the knife to be grasped by the operator for severing and to prevent the web's passing 35 a second time around the platen.
